UNITED STATES PATENT OFFICE.

JAMIE H. BATCHELOR, OF SAVANNAH, GEORGIA, ASSIGNOR TO CARL ESPY, OF SAVANNAH, GEORGIA.

FUEL-HEATING DEVICE.

1,228,517.

Specification of Letters Patent.

Patented June 5, 1917.

Application filed June 17, 1916. Serial No. 104,245.

To all whom it may concern:

Be it known that I, JAMIE H. BATCHELOR, a citizen of the United States, residing at Savannah, in the county of Chatham and State of Georgia, have invented certain new and useful Improvements in Fuel-Heating Devices, of which the following is a specification, reference being had to the accompanying drawings.

10 This invention relates to certain improvements in fuel heating devices and has relation more particularly to a device of this general character especially designed and adapted for use in connection with internal combustion engines; and it is an object of the invention to provide a device of this general character having novel and improved means whereby low grade hydrocarbon liquid may be employed for fuel with a maximum of efficiency.

20 The invention has for a still further object to provide a device of this general character whereby the vapor or mixture may be caused to travel to the engine in differing paths, together with means for controlling the direction of travel of the vapor or mixture.

It is also an object of the invention to provide a novel and improved device of this general character wherein two paths of travel for the mixture or vapor is afforded which are of differing lengths and wherein one of said paths or courses is provided with means for collecting any heavy particles of fuel which may be carried by the vapor or mixture and also to collect any residue which may be carried thereby, together with means whereby the matter so collected may be returned to the intake pipe.

40 The invention consists in the details of construction and in the combination and arrangement of the several parts of my improved fuel heating device whereby certain important advantages are attained and the device is rendered simpler, less expensive and otherwise more convenient and advantageous for use, all as will be hereinafter more fully set forth.

50 The novel features of the invention will hereinafter be definitely claimed.

In order that my invention may be the better understood, I will now proceed to describe the same with reference to the accompanying drawings, wherein—

55 Figure 1 is a somewhat diagrammatic view

partly in elevation and partly in section illustrating a fuel heating device constructed in accordance with an embodiment of my invention;

Fig. 2 is an enlarged fragmentary view 60 partly in section and partly in elevation illustrating certain details of my invention as herein embodied;

Fig. 3 is a view in top plan of one of the rotatable fan members herein disclosed; 65

Fig. 4 is a view in top plan with the top disk omitted of a second fan member as herein embodied;

Fig. 5 is a longitudinal sectional view taken through the valve as herein included; 70

Fig. 6 is a sectional view taken substantially on the line 6—6 of Fig. 1 with the casing omitted; and

Fig. 7 is a sectional view taken substantially on the line 7—7 of Fig. 1 with the casing omitted.

As disclosed in the accompanying drawings, C denotes a carburetor of any ordinary or preferred type and from which leads the intake pipe I, and in communication with said intake pipe I at a predetermined point intermediate its length and at diametrically opposed points, are the longitudinally spaced pairs of headers 1 and 2, the upper headers 1 being preferably of a length greater than the headers 2, and each of said headers 1 is provided with a port 3 affording communication with the cylinders (not shown) of an internal combustion engine.

The outer extremities of the adjacent 90 headers 1 and 2 have in communication therewith the pipes 4 substantially U-shaped in form and of any predetermined number but preferably three as indicated in Fig. 7 of the accompanying drawings, and said pipes 4 are preferably flattened as indicated in said Fig. 7 in order to afford an increased heating surface.

The pipes 4 and headers 1 and 2 together with the adjacent portion of the intake pipe I are inclosed within the exhaust jacket J whereby it will be perceived that the vapor or mixture passing through the headers 1 and 2 and pipes 4 will be effectively heated, it being understood that the vapor or mixture passing through the pipes 4 will be brought to a higher temperature as may be demanded by the requirements of practice and particularly in the starting of the engine or motor. The exhaust gases may be con- 110

ducted within the jacket J in any desired manner or if preferred the jacket J may act as an exhaust manifold and one end of the jacket is provided with an exit A. As the 5 particular means whereby the exhaust gases are delivered within the jacket forms no particular part of my present invention, it is thought that a detail description and illustration thereof is unnecessary.

10 The direction of flow of the vapor or mixture is under control of the hollow valve member V rotatably mounted within the intake pipe I and provided with the properly positioned ports 5 adapted to register with 15 the inner ends of the headers 1 and 2. It is to be understood that when the upper ports 5 of the valve member V are in communication with the upper headers 1, the lower ports 5 are out of register with the 20 lower headers 2.

The valve member V may be operated in any desired manner and as herein disclosed its upper closed end 6 has operatively engaged therewith the rod 7 provided with an 25 operating member 8 herein disclosed as a hand lever, although I do not wish to be understood as limiting myself to this exact arrangement.

The lower end of the valve member V is 30 open and said open end has disposed thereacross the perforate disk 9 preferably of gauze which serves to retain within the valve member V the filler 10 of suitable filtering material and preferably granulated coke. It 35 is also to be noted in Fig. 2 that the ports 5 have disposed thereacross the perforate disks or plates 11 preferably of gauze to assure the maintenance of the filler 10 within the valve member V.

40 The intake pipe I has interposed therein at a point preferably below the jacket J the fan casing F of a radius materially in excess of the radius of the intake pipe I and in which are mounted the reversely movable 45 rotatable fan elements E and E'.

The fan element E comprises, as herein embodied, a disk 12 of a radius substantially equal to the radius of the casing F and is provided at its marginal portion with the 50 upstanding curved blades 14. At its axial center the disk 12 is suitably affixed to the tubular shaft 15 which extends exteriorly of the intake pipe I and has secured to its exterior portion an operating pulley 16. 55 The disk 12 is also provided at its central part with the concentric series of openings 17 in communication with the intake pipe I and through which the vapor or mixture is adapted to be drawn.

60 The fan element E' includes a disk 18 having a hole 19 in the center, said hole being of the same radius as the intake pipe I and with which the openings or perforations 17 communicate. The member 18 is 65 provided with the upstanding blades 20 dis-

posed on a suitable curvature but in a direction opposite to the blades 14 of the fan element E, and said blades 20 intersect the opening 19 and are secured at their inner ends to the shaft 21 disposed through the tubular shaft 15 and exteriorly thereof and having affixed to its extended portion the pulley 22. The upper margins of the blades 20 have secured thereto the imperforate disk 23 which is also secured to the inner extremity of the shaft 21 and whereby it will be perceived that the vapor or mixture drawn within the casing F will be prevented from passing directly therethrough.

70 The shafts 15 and 21 are adapted to be 80 coupled in any suitable manner with a desired movable part or parts of the engine or motor and are to be rotated in opposite directions, as indicated by the arrows a and b in Fig. 1 of the accompanying drawings. 85 By this arrangement it will be perceived that the heavy particles of fuel included within the mixture or vapor will be thoroughly broken and furthermore it will be perceived that the curvature of the blades 14 90 and 20 are such as to throw the mixture or fuel outwardly toward the side wall 24 of the casing F. This action also results in the separation from the mixture or vapor any residue such as tar which may be included 95 therein. It is also to be noted that the blades 14 and 20 are of a height less than the corresponding dimension of the casing F so that the vapor or mixture may be sucked or drawn by the engine or motor from within 100 the casing F in a manner and for a purpose which is believed to be clearly apparent to those skilled in the art to which my invention appertains.

I also find it of advantage to provide the 105 bottom of the casing F with the tapped opening 25 to facilitate the cleansing of the interior of the casing F which is preferably done through the use of kerosene.

110 Each of the headers 1 at a point in advance of the port 3 in communication therewith, is provided with the upstanding baffle plate 26 which is of a height substantially equal to one-half of the vertical dimension 115 of said headers and which serves as a further means to collect any heavy particles of gas or residue which may be carried by the mixture or vapor when the same is caused to pass through the pipes 4, and in communication with each of said headers 1 at a point 120 in advance of the baffles 26 are the return pipes 27 leading to the intake pipe I preferably at a point intermediate the fan casing F and the butterfly valve B interposed in 125 said intake pipe I and as is indicated in Fig. 1 of the drawings.

In practice upon the starting of the motor or engine the valve member V is adjusted so as to bring the lower ports 5 thereof in communication with the lower headers 2, 130

whereby it will be perceived that the mixture or vapor will travel through the pipes 4 to the ports 3 and whereby the heat of the exhaust gases will increase the temperature 5 of said vapor or mixture. When the engine is in continued operation, the valve member V may be so adjusted as to bring the upper ports 5 in register with the upper headers 1 and shut off the lower headers 2, 10 whereupon it will be perceived that the vapor or mixture will pass directly through the valve member V and to the ports 3 through the headers 1 only. It will also be understood that the adjustment of the valve member V may be effected whenever the necessities of practice deem the same to be essential.

From the foregoing description, it is thought to be obvious that a charge forming 20 device constructed in accordance with my invention is of an extremely simple and comparatively inexpensive nature and is particularly well adapted for use by reason of the convenience and facility with which 25 it may be assembled, and it will also be obvious that my invention is susceptible of some change and modification without material departure from the principles and spirit thereof and for this reason I do not 30 wish to be understood as limiting myself to the precise arrangement and formation of the several parts herein shown in carrying out my invention in practice, except as hereinafter claimed.

35 I claim:

1. A fuel heating device, comprising headers in communication with an intake pipe and in spaced relation longitudinally of the intake pipe, one of said headers being 40 provided with an outlet port, a pipe disposed in an irregular path in communication with the outer ends of the headers, a valve for controlling the flow from the intake pipe to the header provided with the outlet port and through the pipe connecting the headers, and a jacket incasing the intake pipe, the headers and the pipe connecting the headers, said jacket being in communication with a source of heat.

50 2. A fuel heating device comprising headers in communication with an intake pipe and in spaced relation longitudinally of the intake pipe, one of said headers being provided with an outlet port, a pipe 55 disposed in an irregular path in communica-

cation with the outer ends of the headers, a valve for controlling the flow from the intake pipe to the header provided with the outlet port and through the pipe connecting the headers, a baffle plate partially intersecting the header provided with the outlet port and positioned at a point intermediate said outlet port and the outer end of the header, and a jacket incasing the intake pipe, the headers and the pipe connecting the headers, said jacket being in communication with a source of heat.

3. A fuel heating device comprising headers in communication with an intake pipe and in spaced relation longitudinally of the intake pipe, one of said headers being provided with an outlet port, a pipe disposed in an irregular path in communication with the outer ends of the headers, a valve for controlling the flow from the intake pipe to the header provided with the outlet port and through the pipe connecting the headers, a baffle plate partially intersecting the header provided with the outlet port and positioned at a point intermediate said outlet port and the outer end of the header, a return pipe leading from the header at a point in advance of the baffle plate and discharging within the intake pipe, and a jacket incasing the intake pipe, the headers and the pipe connecting the headers, said jacket being in communication with a source of heat.

4. A fuel heating device comprising headers in communication with an intake pipe and in spaced relation longitudinally of the intake pipe, one of said headers being provided with an outlet port, a pipe disposed in an irregular path in communication with the outer ends of the headers, a valve for controlling the flow from the intake pipe to the header provided with the outlet port and through the pipe connecting the headers, said valve being hollow and provided with a filler of filtering material, and a jacket incasing the intake pipe, the headers and the pipe connecting the headers, said jacket being in communication with a source of heat.

In testimony whereof I hereunto affix my signature in the presence of two witnesses.

JAMIE H. BATCHELOR.
